US0D1100051S

(12) **United States Design Patent** (10) Patent No.: **US D1,100,051 S**
(45) Date of Patent: ** Oct. 28, 2025

(54) **TOSS GAME**

(71) Applicant: **Julian Daniel Mauz**, Schwendi (DE)

(72) Inventor: **Julian Daniel Mauz**, Schwendi (DE)

(**) Term: **15 Years**

(21) Appl. No.: **35/522,385**

(22) Filed: **Sep. 16, 2023**

(80) **Hague Agreement Data**

Int. Filing Date: **Sep. 16, 2023**

Int. Reg. No.: **DM/233229**

Int. Reg. Date: **Sep. 16, 2023**

Int. Reg. Pub. Date: **Sep. 20, 2024**

(30) **Foreign Application Priority Data**

Sep. 11, 2023 (EM) 015033801-0001

(51) LOC (15) Cl. **21-01**

(52) U.S. Cl.

USPC **D21/303**; D21/302

(58) **Field of Classification Search**

USPC D21/300, 301, 302, 303, 310, 436, 699;
D19/136, 178, 179, 180

CPC A63F 9/06; A63B 67/0204

See application file for complete search history.
